United States Patent Office

Des. 226,577
Patented Mar. 27, 1973

226,577

PENDANT OR THE LIKE

Charlotte Linnea Schwarz, Bridgeport, Conn., assignor to Wallace Silversmiths, Inc.

Filed Feb. 9, 1972, Ser. No. 225,018

Term of patent 14 years

Int. Cl. D11—01

U.S. Cl. D45—17

FIG.1

FIG.3

FIG. 1 is a front elevation of a pendant or the like showing my new design;

FIG. 2 is a side elevation thereof;

FIG. 3 is a rear elevation thereof;

I claim:

The ornamental design for a pendant or the like, substantially as shown.
